CLAIM

The ornamental design for a display screen or portion thereof with a graphical user interface with navigation icons for native super application channels, as shown and described.

DESCRIPTION

FIG. 1 is a front view of a first embodiment of a display screen or portion thereof with a graphical user interface with navigation icons for native super application channels showing my new design;

FIG. 2 is a front view of a second embodiment thereof;

FIG. 3 is a front view of a third embodiment thereof;

FIG. 4 is a front view of a fourth embodiment thereof; and,

FIG. 5 is a front view of a fifth embodiment thereof.
